United States Patent Office.

PHILIPP SCHREYER, OF NEW YORK, N. Y.

Letters Patent No. 101,770, dated April 12, 1870.

IMPROVEMENT IN MONEY-SAFES.

The Schedule referred to in these Letters Patent and making part of the same.

To all whom it may concern:

Be it known that I, PHILIPP SCHREYER, of the city of New York, in the county and State of New York, have invented a new and improved Money-Safe; and I do hereby declare that the following is a full, clear, and exact description thereof, which will enable others skilled in the art to make and use the same, reference being had to the accompanying drawings forming part of this specification.

Figure 1 represents a vertical central section of my improved money-safe.

Figure 2 is a horizontal section of the same, taken on the plane of the line x x , fig. 1.

Figure 3 is a horizontal section of the same, taken on the plane of the line y y , fig. 1.

Similar letters of reference indicate corresponding parts.

This invention relates to a new manner of constructing iron safes, and to a novel method of applying the same to articles of furniture.

The invention consists, first, in so constructing a safe of an outer and inner metal case, that the two cases are only connected by a bolt or bolts passing through their bottoms, no other fastening being required.

The invention consists also in constructing such safes so that they can be applied as supports or standards to tables, as hereinafter more fully described.

A in the drawing represents the outer shell or case of my improved metal safe.

It is made of cylindrical, prismatic, or of other suitable form, with vertical sides, and is open at both ends.

The entire shell is to be made of one single piece of metal.

In the shell A are secured two rings, a and b , one near the upper and the other near the lower end, as shown in fig. 1.

These rings are riveted or otherwise securely fixed in their respective places.

B is the inner shell or case of the safe. It is about as long as the outer case, but of smaller cross-section or diameter.

Close to its upper end is firmly secured around the case B a ring or projecting flange, c .

When the case B is inserted in the outer shell A,

it is suspended in the latter by its flange c , which rests upon the ring a , as shown.

The ring a serves not only to support the case B, but also to close the upper end of the annular space d , which is formed between the two cases as shown.

For this purpose an inward-projecting supporting-flange, e , may be formed on the ring a , as shown.

Within the case B is secured, at the lower end, an inward-projecting ring, f , which serves to support the upper bottom C.

The lower bottom D is placed against the lower edge of the ring b .

The case A is placed upon a plate, E, which forms the supporting bottom of the entire apparatus.

Suitable legs F sustain the plate E.

A bolt, G, having a head, g , to fit under the lower bottom D, and passing the plates C and E, as shown, to receive nuts h and i at both ends, serves to lock all the parts firmly together, and constitutes the sole fastening device. It also holds the bottoms against their several supporting-rings.

Two or more such bolts may be used if desired.

The upper end of the inner case is closed either securely by a plate or by the removable door and lock H. The door may, however, be arranged in the side of the safe, in which case it would constitute part of the two shells.

Non-heat-conducting material is put into the space between the shells and bottoms.

A projecting ring, T, made of wood or other material, may be fastened to the upper part of the safe, to serve as a table-top. The safe will, in that case, form the standard or support of the table.

Having thus described my invention,

I claim as new and desire to secure by Letters Patent—

1. The safe constructed of the shells A and B and bottoms C, D, and E, all parts being connected by means of bolts G, passing through the bottom, as set forth.

2. The money-safe and table, formed of the ring T and legs F, shells A and B, bottoms C D E, and bolt G, all constructed and fitted together in the manner shown and described.

Witnesses: PHILIPP SCHREYER.
